CLAIM

The ornamental design for three dimensional computer generated icon for a display screen, as shown and described.

DESCRIPTION

FIG. 1 is a front view of a three dimensional computer generated icon for a display screen; FIG. 2 is a front view of a second embodiment thereof; FIG. 3 is a front view of a third embodiment thereof; and, FIG. 4 is a front view of a fourth embodiment thereof. The broken line drawing of a display screen in all the views is for illustrative purposes only and forms no part of the claimed design.
